UNITED STATES PATENT OFFICE.

THOMAS F. PEARSON, OF BILLERICA, MASSACHUSETTS.

CASH-REGISTER.

1,085,755.

Specification of Letters Patent. Patented Feb. 3, 1914.

Application filed March 31, 1913. Serial No. 757,911.

To all whom it may concern:

Be it known that I, THOMAS F. PEARSON, a citizen of the United States, residing at Billerica, in the county of Middlesex and State of Massachusetts, have invented certain new and useful Improvements in Cash-Registers, of which the following is a specification.

My invention relates to pocket counters or cash registers. It is intended to be used more particularly for registering cash collections, sales or expenditures and it is of such size that it can readily be carried in the pocket and used as a pencil holder.

My device may be made small and compact and at the same time without any fine scales or graduations which might make it difficult to handle. It may be made with different scales for different purposes.

In the drawings, Figure 1 is an elevation. Fig. 2 is an elevation with parts broken away to show the interior construction. Fig. 3 is a view from the top on line X—Y of Fig. 1. Fig. 4 is a view from the top on line S—T of Fig. 1. Fig. 5 is a view from the top on line U—V of Fig. 1. Fig. 6 is a view from the top on line W—Z of Fig. 1. Fig. 7 is a view from the top on line O—P of Fig. 1. In Figs. 3, 4, 5, 6 and 7 the parts broken away or shown in section in Fig. 2 are shown complete and in place.

The principal features of my device are a casing A which is relatively stationary; a barrel B revoluble in the casing and which has longitudinal slots 22; a threaded spindle C which is revoluble with the casing A or stationary therewith; a band or marker D slideable on barrel B and arranged to engage the threads of spindle C whereby when the barrel B is rotated, marker D will be forced by its engagement with the threads of spindle C to slide back and forth. I also provide a cap F rotatable in casing A preferably in the same direction with barrel B.

The casing A is preferably tubular and is divided by a transverse partition 10 as shown in Figs. 2 and 4. This partition has an opening 11 which conforms to the shape of spindle C which at that point is flattened or cut away on opposite sides whereby it can not turn in opening 11. If dollars and cents are to be registered, at its bottom, casing A is provided with twenty teeth 12 which rake toward the right as shown in Fig. 1. It also has a pointer 13 which indicates a tooth which corresponds with the

zero of the device. At the top, its circumference is divided into five equal parts by notches 14, four of which rake toward the right, while the fifth which is in line with pointer 13 is a locking notch 15 with parallel sides.

The barrel B is of such size as to fit revolvably inside of casing A and at that end has a collar 20 which encircles it and is preferably soldered or brazed into place. The edge of collar 20 adjoining teeth 12 of casing A is formed with twenty teeth 21 which engage teeth 12 and rake toward the left. These teeth are numbered as shown, preferably from zero represented by the dollar sign, in 5's and 10's up to 100. At the opposite end, barrel B carries another collar or pencil holder H which is preferably soldered thereon. It has a scale which may be from zero to fifty marked lengthwise on one or both of the slots 22 which extend longitudinally through barrel B. Preferably zero begins at the upper edge of holder H. Near the bottom of barrel B is a partition 24 which may be held in place by means of ears 25 which enter depressions 26 in the wall of barrel B. A radial slot 27 permits the lower end of spindle C to be slid in place in the center of partition 24 while the parts are being assembled and before holder H is put in place. This partition serves as the bottom bearing for spindle C and partition 10 serves as the top bearing. Preferably collars 30 and 31 are fixed near the end of spindle C to prevent any longitudinal action between spindle C and barrel B. Spindle C at its lower portion 33 is cylindrical and is threaded with a one in twenty pitch. It has at exactly the right predetermined place near the upper end of the threaded portion 33 a finger 34 which extends outward and serves as a lock as will be described hereafter.

The marker D consists of a band slideable on the outside of barrel B and provided with a catch which comprises a push button or member 40 which extends through suitable openings in marker D and also through both slots 22 in barrel B. Near its middle portion, member 40 is formed as a ring 41 extending loosely around spindle C and adapted at one point to fit the threads thereof as shown in Fig. 6. A compression spring 42 normally tends to hold 41 in engagement with the threads on C. By pressing on the end 43 of member 40 which pref-

erably has a slot for the reception of the thumb nail, 41 may be disengaged from the threads on spindle C so that the marker D may be slid freely back and forth on barrel B. I preferably provide a nose 45 attached to ring 41 in such a position that when marker D has risen to a predetermined point, nose 45 will strike finger 34 and prevent further turning.

- 10 Before starting to use the device, the parts are so adjusted that zero or the dollar sign on the tooth scale of collar 20 is turned to pointer 13 and the marker D is slid down until its lower edge coincides with zero on 15 the slide scale marked along the length of slots 22 in barrel B. The scale on 20 which I will call the tooth scale is intended to register the cents, preferably in 5's and 10's up to one dollar, while the scales along slots 20 22 which I will call the slide scale is intended to register the dollars from zero to fifty.

To hold barrel B in engagement with casing A, I provide a collar or nut 36 fastened to spindle C at a point above partition 10, and between it and partition 10 I place a compression spring 37. Barrel B may therefore be turned with the fingers as the teeth 21 ride over teeth 12 and lock themselves in place whenever the turning is 30 stopped.

Cap F comprises an outside section 50 which is cylindrical, headed and knurled at 51 and of the same diameter as casing A against the end of which it rests. The cap 35 inside 52 fits just inside of 50 and therefore inside of casing A and is attached to 50 by means of a screw 53 or by any other suitable device. Its bottom 54 has a circular opening to permit spindle C to turn therein. 40 A washer 55 having an opening which fits the flattened or cutaway portion of spindle C as shown in Fig. 3 revolves therewith and serves as a bearing for compression spring 56 between it and a collar 57 fixed on 45 spindle C. This spring and collar hold cap F elastically in engagement with the end of casing A. The end of casing A has notches 14 and 15 as described while the adjoining edge of cap F has a single tooth 58 which 50 fits notch 15 and which can readily be slid over and into notches 14. Cap F in connection with marker tooth 58 and the scale 17 on the upper end of casing A is used to 55 count the pennies for instance from one to five. When five is reached, marker tooth 58 drops into notch 15 and indicates by the additional force required to disengage it, that scale 21 should be turned one tooth corresponding to five. In this way, any 60 amount from one cent to fifty dollars can be counted.

In place of the holder H, any other suitable device may be used to limit the downward motion of marker D. The nose 45 65 is so placed and adjusted as is also finger

34 that they will engage at the time when the bottom edge of the marker D has reached the upper limit or the 50 mark of the slide scale. Its motion is thus positively limited.

The casing A may be ornamented in any desired manner and may be of any desired form such as octagonal, etc., provided the working parts are not affected.

The tooth scale may run from one to ten for instance and the slide scale may be divided with reference thereto. In such cases, the pitch of the screw must be adapted to conform. The parts may be arranged to count English money, pounds, shilling and pence, or they may be arranged to count 80 any other money or things.

The cap F need not be used, or it may, if desired, be omitted entirely, but I prefer to use it.

In using the device, cap F is naturally held in the left hand and barrel B in the right. Barrel B is turned from the operator or to the right in Figs. 1 and 2 and teeth 21 ride over teeth 12 against the action of both springs 56 and 37. When it is desired to count cents on scale 17, the hands are pulled apart and as cap F is acted on only by spring 56 while B is acted on by 56 and 37, cap F is pulled away from casing A and barrel B can be turned toward the operator. When it is moved in this direction, the oppositely pitching teeth 21 and 12 engage and thereby casing A turns with B as far as the registration desired.

What I claim as my invention and desire to cover by Letters Patent, is:

1. In a counting device, a casing having teeth, a barrel revoluble in the casing and which has a tooth scale and teeth which engage the teeth on the casing and which has longitudinal slots and a slide scale, combined with a spindle so fixed in the casing as to revolve therewith and which has screw threads and extends into the barrel, and a marker slidable on the barrel and in engagement with the screw threads on the spindle.

2. In a counting device, a cylindrical casing having teeth at one end, a spindle revoluble with the casing and having screw threads, a barrel revoluble in the casing having teeth in engagement with the casing teeth and a scale marked thereon and having longitudinal slots and a scale marked thereon, and a marker slidable on the barrel, together with a catch carried by the marker which normally engages the threads on the spindle but which may be disengaged therefrom.

3. In a counting device, a cylindrical casing having teeth at one end and notches at the other end and a transverse partition, a cap revoluble in the casing in the end adjoining the notches and having a tooth in engagement with the notches, a barrel revoluble in the end of the casing adjoining the

teeth having teeth which engage the casing teeth and a scale marked thereon also having longitudinal slots with a slide scale marked thereon, a spindle one end of which passes through the partition in the casing and is revolvable therewith and which passes through the cap and is revolvable therein being elastically connected longitudinally with the cap and casing and which has a screw thread at the other end, a finger attached to the spindle, and a marker slidable on the barrel, together with a catch carried by the marker adapted to engage or disengage the screw threads on the spindle and having a nose adapted to engage the finger on the spindle as described.

4. In a counting device, a cylindrical casing having teeth at one end, a spindle revolvable with the casing and slidable elastically lengthwise therein and having screw threads, a barrel revolvable in the casing and slidable with the spindle having teeth in engagement with the casing teeth and a scale marked thereon and having longitudinal slots and a slide scale, and a marker slidable on the barrel, together with a catch carried by the marker which normally engages the threads on the spindle but which may be disengaged therefrom.

5. In a counting device, a cylindrical casing having teeth at one end and notches at the other end, a spindle revolvable with the casing and slidable elastically lengthwise therein and having screw threads, a barrel revolvable in the end of the casing adjoining the teeth in the casing and slidable with the spindle having teeth which engage the casing teeth and a scale marked thereon and

having longitudinal slots and a slide scale marked thereon, a cap revolvable in the end 40 of the casing adjoining the notches and having a tooth in engagement therewith said cap being elastically slidable lengthwise in the casing, and a marker slidable on the barrel, together with a catch carried by the 45 marker which normally engages the threads on the spindle but which may be disengaged therefrom.

6. In a counting device, a cylindrical casing having teeth at one end and notches at 50 the other end, a spindle revolvable with the casing and slidable lengthwise therein and having screw threads, a barrel revolvable in the end of the casing adjoining the teeth in the casing and slidable with the spindle having 55 teeth which engage the casing teeth and a scale marked thereon and having longitudinal slots and a slide scale marked thereon, a cap revolvable in the end of the casing adjoining the notches and having a tooth in engagement therewith said cap being slid- 60 able lengthwise in the casing, a marker slid- able on the barrel, a catch carried by the marker arranged to engage or disengage with the threads on the spindle, means at- 65 tached to the spindle for holding the barrel and casing in elastic contact, and other means attached to the spindle for holding the cap and casing in elastic contact.

In testimony whereof I, hereto affix my 70 signature in presence of two witnesses.
